UNITED STATES PATENT OFFICE.

WILLIAM M. SMITH, OF WEST MERIDEN, CONNECTICUT, ASSIGNOR TO
MERIDEN BRITANNIA COMPANY, OF SAME PLACE.

DESIGN FOR A COFFIN-PLATE.

Specification forming part of Design No. **8,056**, dated February 9, 1875; application filed January 18, 1875.
[Term of Patent 14 years.]

To all whom it may concern:

Be it known that I, WM. M. SMITH, of West Meriden, in the county of New Haven and State of Connecticut, have invented a new Design for a Coffin-Plate; and I do hereby declare the following, when taken in connection with the accompanying drawings and the letters of reference marked thereon, to be a full, clear, and exact description of the same, and which said drawings constitute part of this specification, and represent a face view.

This invention relates to a design for the inscription-plate for coffin, and consists in the configuration or outline of the plate, as hereinafter described, and shown in the accompanying illustration.

The general appearance of the plate is that of a piece of ribbon, the two ends folded. The center portion of the plate is curved upon

its edges to give it the appearance of an oval or curved surface. Near the ends the edges are cut and transverse lines formed in the surfaces to give to the ends the appearance of being partially or loosely folded, as clearly seen in the accompanying illustration. The surface may be ornamented to suit the demand of the trade, that being no part of the invention.

I claim—

The design for a coffin-plate, consisting of the center, the ends of which represent partially-closed folds, as herein described, and shown in the accompanying illustration.

WILLIAM M. SMITH.
